UNITED STATES PATENT OFFICE.

JOHN HARRISON, OF SANTA RITA, NEW MEXICO, ASSIGNOR OF ONE-THIRD TO
CHARLES L. MCALLISTER AND ONE-THIRD TO WILLIAM F. SHEA, BOTH OF
SANTA RITA, NEW MEXICO.

RAILWAY-SWITCH.

1,111,653.

Specification of Letters Patent. Patented Sept. 22, 1914.

Application filed June 27, 1914. Serial No. 847,603.

To all whom it may concern:

Be it known that I, JOHN HARRISON, a citizen of the United States, residing at Santa Rita, in the county of Grant and State of New Mexico, have invented certain new and useful Improvements in Railway-Switches; and I do hereby declare the following to be a full, clear, and exact description of the invention, such as will enable others skilled in the art to which it appertains to make and use the same.

My invention relates to new and useful improvements in railway switches and resides in the provision of an improved switch with means of novel construction whereby the switch points may be adjusted relative to the stock rails independently of each other.

Another important object is to provide simple and inexpensive means to adjust the switch points relative to each other so that the proper operation of the points is insured, said means being locked in adjusted position and operatively connected with the switch throwing or operating means.

The above and additional objects are accomplished by such means as are illustrated in the accompanying drawings, described in the following specification and then more particularly pointed out as claimed.

With reference to the drawings, wherein I have illustrated the preferred embodiment of my invention as it is reduced to practice, and throughout the several views of which similar reference numerals designate corresponding parts, Figure 1 is a plan view of a switch showing my improved adjusting means therefor in position, Fig. 2 is a side elevation of the adjusting means removed from the switch point, and Fig. 3 is a detail perspective views showing the manner of adjusting the ends of one of the switch adjusting members.

Referring to the drawings by characters of reference, A and B designate stock rails of a switch and 1 and 2 the switch point rails arranged between the rails A and B in the ordinary manner. I provide means designated 3 as an entirety that is connected with the switch points and consists of an adjusting bar 4 that is to rest flat upon the road bed or surface upon which the rails A and B are placed and is bent at its ends to

provide vertically and angularly disposed portions 5 and 6. At the free ends of the portions 5 and 6 the bar 4 is bent to provide right angularly extending flanges or lugs 7 and 8 that are apertured and designed to co-operate with L-shaped plates 9 that are secured by suitable fastening means to the portions 5 and 6 and have their longer arm portions opposed to the lug or flange 7 in spaced relation thereto. Openings are provided in the longer portions of the L-shaped plates 9 which align with the openings in the lugs 7. An angular clamp 10 is carried by the bar at a point adjacent to the center thereof and is secured to the switch point 2 by suitable fastening means 11 adjacent to the pointed end of said point. A rod 12 provided with screw threads at one end is inserted through the lug or flange 8 and corresponding plate 9 at its screw threaded end. The portion 5 of the bar 4 and corresponding parts are arranged outside of the track A. A nut or internally threaded adjusting member 13 is mounted between the lug 8 and plate 9 and receives the screw threaded portion of the bar 12. The bar 12 is provided at its outer end with an eye 14 that is to be connected with the switch throwing or operating mechanism, not shown.

It will be readily seen that the bar 12 in being adjustable relative to the bar 4 facilitates the connection of the device with various characters of switch operation mechanism and when the mechanism is positioned at different points relative to the switch. An opening 15 is provided in the body portion of the bar 4 in spaced relation to the clamping member 10 so that the clamping member may be positioned at said opening and secured by a bolt or similar fastening means and co-operate with a different character of switch. The portion 6 is positioned about midway between the points 1 and 2 and has an adjusting nut 16 carried thereon between the plate 9 and flange or lug 7, which nut aligns with the apertures or openings in the opposed portion of the plate and flange. A relatively flat bar 18 carrying a clamping member 19 is connected by said clamping member 19 to the switch point 1. The inner end of this bar 18 is rounded and threaded as at 20 and inserted through the lug 7, nut 16 and

L-shaped plate 9. A set screw 21 is carried by the portion 6 in such manner as to be turned into engagement with the nut 16 to effect the locking thereof.

5 In operation when it is desired to adjust the points relative to the stock rails A and B the nut 16 is turned so that the bars 18 and 4 are moved in the direction to effect the desired adjustment. The set screw 21 10 is then turned to engage the nut 16 to effect the locking thereof and prevent accidental derangement. It will be readily seen that I have provided a safety adjustment for switches that will permit the easy and reliable adjusting of the switch point in a short time.

In practice, I have found that the form of my invention, illustrated in the drawings and referred to in the above description, as 20 the preferred embodiment, is the most efficient and practical; yet realizing that the conditions concurrent with the adoption of my device will necessarily vary, I desire to emphasize the fact that various minor 25 changes in details of construction, proportion and arrangement of parts may be resorted to, when required, without sacrificing any of the advantages of my invention, as set forth.

30 What is claimed is:—

1. The combination with the switch points of a switch of a bar secured intermediate its ends to one of the switch points and being bent at its ends to extend right 35 angularly to its body portion, said angularly bent portion being provided at its free end with a right angularly extending lug, L-shaped members secured adjacent to the ends of said bar and having certain 40 portions thereof disposed in spaced parallel

relation to said last named right angularly bent portion, a bar secured at one end to the other switch point having its other end threaded and extended through the adjacent angularly bent portion and L-shaped plate 45 opposed thereto, a nut mounted on the screw threaded portion of the bar and between the angularly bent portion and L-shaped plate, a bar inserted through the angularly bent portion at the opposite end of the first 50 named bar and opposed L-shaped plate, a nut between said angularly bent portion and L-shaped plate and upon said bar, said bar to be connected with switch throwing apparatus and means to lock said first named 55 nut in adjusted position.

2. The combination with a switch point of a railway switch of a bar secured intermediate its ends to one of the switch points, a right angularly extending lug on each end 60 of said bar, L-shaped members secured adjacent to the ends of said bar and having certain portions thereof disposed in spaced parallel relation to said lugs, a bar secured to the other switch point and being reduced 65 and threaded at one end and extending through aligned threaded openings in the adjacent lug and L-shaped member, a nut mounted on the screw threaded portion that is extended through the adjacent L-shaped 70 member and a bar adjustingly connected with the L-shaped member and lug at the other end of said first named bar.

In testimony whereof I affix my signature in presence of two witnesses.

JOHN HARRISON.
